(57) CLAIM

The ornamental design for a mirror as shown and described.

DESCRIPTION

FIG. 1 is a perspective view of a first embodiment of a mirror showing my new design;

FIG. 2 is a front view of the design shown of FIG. 1;

FIG. 3 is a rear view of the design shown of FIG. 1;

FIG. 4 is a left side view of the design shown of FIG. 1;

FIG. 5 is a right side view of the design shown of FIG. 1;

FIG. 6 is a top view of the design shown of FIG. 1;

FIG. 7 is a bottom view of the design shown of FIG. 1;

FIG. 8 is a perspective view of a second embodiment of a mirror showing my new design;

FIG. 9 is a front view of the design shown of FIG. 8;

FIG. 10 is a rear view of the design shown of FIG. 8;

FIG. 11 is a left side view of the design shown of FIG. 8;

FIG. 12 is a right side view of the design shown of FIG. 8;

FIG. 13 is a top view of the design shown of FIG. 8; and,

FIG. 14 is a bottom view of the design shown of FIG. 8.

The break lines shown in the middle portions of the mirror in the Figures indicate that the appearance of any portion of the article between the break lines forms no part of the claimed design. The dash-dot-dash lines illustrate an unclaimed boundary of the claimed design. The broken lines in the Figures illustrate portions of the mirror that form no part of the claimed design.

1 Claim, 10 Drawing Sheets
